[57] CLAIM

I claim the ornamental design for a barbecue stand, as shown and described.

DESCRIPTION

FIG. 1 is a top, front and side perspective view of a barbecue stand showing my new design;
FIG. 2 is a front elevational view thereof;
FIG. 3 is a bottom plan view thereof;
FIG. 4 is a side elevational view thereof; and,
FIG. 5 is a rear elevational view thereof.
